(57) **CLAIM**

The ornamental design for a wildlife feeder timer, as shown and described.

DESCRIPTION

FIG. 1 is a front and side perspective view of a wildlife feeder timer showing my new design;

FIG. 2 is a front view thereof;

FIG. 3 is a bottom view thereof;

FIG. 4 is a left side view thereof;

FIG. 5 is a right side view thereof;

FIG. 6 is a top plan view thereof;

FIG. 7 is a bottom plan view thereof;

FIG. 8 is an enlarged front and side perspective view of the wildlife feeder timer shown in FIG. 1; and,

FIG. 9 is an enlarged front view of the wildlife feeder timer shown in FIG. 2.

The broken line showing of a logo depicts unclaimed environmental subject matter.
